TIMING SYSTEM

Filed Feb. 19, 1952

UNITED STATES PATENT OFFICE

2,664,949

TIMING SYSTEM

Zack R. Keck, Strathmore, Calif.

Application February 19, 1952, Serial No. 272,323

8 Claims. (Cl. 161—1)

1

The present invention relates to a timing system and more particularly to a control timer and the combination of the control timer with an electrical circuit, having push button switch means therein, providing novel operational advantages subsequently described in greater detail.

The instant application constitutes a continuation in part of my copending application entitled "Time Controlled Starting Switch Actuating Mechanism," Serial No. 247,055, filed September 18, 1951, now Patent No. 2,620,871.

It is well known, and the files of the Patent Office show, that a great number of timing mechanisms have been developed which include electrical switching devices adapted for connection in electrical circuits and timing mechanisms having controlled connection to the switching devices. Such structures usually employ a switch blade movable between predetermined open and closed positions and connection to the timing mechanism of such character that at a predetermined time measured by the timing mechanism the blade is thrust into closed position and held in such position, or thrust into open position and held therein. Although such structures are eminently satisfactory in many electrical environments, their use in others is objectionable because of their limited electrical capacities, their expense, and difficulties of installation, lack of mobility, and other deficiencies.

For one or more of these reasons, such switches are not generally utilized in connection with electrically motivated irrigation pumps and the like. Such pumps are conventionally provided with energizing circuits having master switches in series with their respective pumps. The switches are provided with holding circuits each including a push button start switch and a push button stop switch connected in series. The start switch is spring loaded into a normally open position and the stop switch into a normally closed position. An electrically self-sustaining switch is connected in parallel with the start switch so that when the start switch is closed and released the holding circuit continues to remain closed through the self-sustaining switch until the stop switch is operated. Subsequent operation of the stop switch breaks the circuit and the self-sustaining switch opens so that the holding circuit can only be re-established by operation of the starting switch.

Although a great many control timers have been developed for use in operating conventional

2

electrical switches, such as that shown and described in the patents to Hughes et al., No. 511,527, Copeman, No. 1,104,781, Copeman No. 1,180,571, Streng, No. 1,191,745, White, No. 1,292,189, Schultz, No. 1,938,155, and many others, none thereof are suitable for use in operating the push button switches in a circuit of the character described in the preceding paragraph. As will subsequently become more clearly apparent, it is important that the start switch be released once it has been operated or the start switch will reclose its circuit immediately following operation and release of the stop switch. This is objectionable not only because of the lack of control which results but in many pumping systems the pump is rotated in a reverse direction with great force for a considerable period immediately following termination of operation thereof, by water or other liquid returning to the position from which it is being lifted by the pump, not infrequently hundreds, and in many instances, thousands of feet therebelow. The untimely restarting of such electrically motivated pumps frequently results in structural failure. Further, it is necessary that the stop switch return to closed position promptly after operation. If this is not done, it is impossible to close the circuit by operation of the start switch. Although many of the control timers alluded to may be dependable in their movement of a switch blade in a single direction, they fail to provide the desired operation and release of great importance in many electrical circuits of the character described.

An object of the present invention is to provide an improved control timer adapted for operation with push button switches and the like.

Another object is to provide a control timer operable to actuate an electrical switching mechanism at a predetermined time as measured by the control timer.

Another object is to provide such a control timer adapted to release switches with which they are associated promptly upon timed actuation thereof.

Another object is to provide a control timer having a plunger mounted for reciprocal rectilinear movement operable to actuate push button switches and the like by momentary engagement of the plunger therewith with the plunger in alignment with the push button so that the rectilinear movement of the plunger minimizes scrubbing and abrading action on the push button.

Another object is to provide releasable means

for mounting a control timer of the character described in selective positions for successive engagement with a plurality of push button switches or the like.

Another object is to provide a combined electrical circuit for a push button start switch and a push button stop switch therein, a bracket in spanning relation to the push button switches, a control timer having a plunger reciprocated at an adjustably predetermined time as measured by the timer, and means for releasably mounting the timer on the mounting means in selected positions with the plunger aligned with the push buttons.

Another object is to provide an improved control timer and mounting means therefor accommodating mobility of the timer and releasable mounting thereof in any of a number of operable positions whereby a single timer by frequent repositioning can be caused to do the work of several timers.

A further object is to provide improved elements and arrangements thereof in a device and system of the character and for the purposes set forth.

Further objects and advantages will become apparent in the subsequent description in the specification.

In the drawing:

Fig. 1 is a side elevation of a conventional push button start switch and the push button stop switch, a mounting panel for the switches, a schematically represented electrical circuit suitable to the employment of such switches, and a side elevation of a bracket and control timer embodying the principles of the present invention.

Fig. 2 is a fragmentary face view of the mounting panel of Fig. 1 showing the face of the mounting bracket supported thereon.

Fig. 3 is a fragmentary side elevation of a mounting panel, push button switches, and modified bracket structure shown in supporting relation to a fragmentarily illustrated control timer of the present invention.

Fig. 4 is a face view of a mounting panel having a push button start switch and a push button stop switch mounted therein showing a pair of brackets of the character shown in Fig. 3 mounted thereon.

Fig. 5 is a fragmentary longitudinal section of the control timer of the present invention.

Fig. 6 is a transverse section of the control timer as taken on line 6—6 of Fig. 1.

Fig. 7 is a fragmentary enlarged longitudinal section of the control timer showing a portion of the structure illustrated in Fig. 5 in a succeeding operational position.

Fig. 8 is a side elevation of a crank shaft employed in the control timer of the present invention.

Referring in greater detail to the drawing:

A mounting panel 10 of any suitable material employs a pair of bolts 11 and a back plate 12 to mount a start switch 13 and a stop switch 14 thereon. The mounting and structure of the switches is for illustrative convenience only and it is to be understood that the present invention is not limited to the precise form thereof shown. A spring 15 is mounted between the plate 12 and the start switch 13 and urges the start switch into a normally open position. A stop spring 16 is mounted between the plate and the stop switch and urges the stop switch into a normally closed position.

A source of electrical energy is represented at

17. An electrically operated double pole switch 18 may conveniently be utilized having an electromagnetic coil 19 and a pair of bridge elements 20 and 21. As shown, the start switch 13 is connected in series with the coil 19 to the source of electrical energy 17. The stop switch 14 is connected electrically in series with the bridging element 20 and with the coil 19 to the source of electrical energy. The stop switch 14, bridging element 20, and coil 19 are electrically in parallel with the series circuit of the start switch 13 and coil 19.

A load circuit 22 serves to connect an electric pump, not shown, or other electrically energized apparatus in series with the bridging element 21.

The structure described to this point is essentially conventional and may depart from the precise form shown without departing from the spirit of the present invention. It will be obvious, that when the start switch 13 is momentarily closed, the coil 19 closes the bridging elements 20 and 21 completing the load circuit 22. When the start switch is released, the electrical path through the stop switch continues to energize the coil 19 so that the bridging elements are held in closed position. When the stop switch 14 is operated with the start switch 13 in normally open position, the circuit to the coil 19 is interrupted so that the bridging elements 20 and 21 return to open position interrupting the load circuit 22. Subsequently, the load circuit can again be completed by operation of the start switch.

A bracket 24 is mounted on the panel 17 in spanning relation to the push button switches 13 and 14, as by bolts 25. The bracket provides an elongated central portion in substantially parallel relation to the panel which has a plurality of substantially equally spaced key hole openings 26 formed therein aligned transversely of the push button switches 13 and 14.

A control timer of the present invention is indicated generally at 30 preferably providing a substantially weatherproof case 31. The case houses a simple and inexpensive timing mechanism indicated generally at 32. It will be obvious that the timing mechanism may be any desired form but the applicant prefers to utilize an inexpensive mechanical clock for the purpose.

Inasmuch as the timing mechanism is essentially conventional, reference is made only to elements thereof to which attention is called for descriptive convenience. Suffice it at this point to observe that the timing mechanism employs a frame 34 secured in the case which mounts a spring driven clock adapted to measure time, to register the time on a clock face 35 and including an alarm system triggered at adjustably predetermined times indicated on the alarm setting face 36.

An alarm control shaft 38 is rotatably mounted in the frame 34 and provides a knurled head 39 exteriorly of the case. The shaft has an end opposite to the head 39 extended into the clock face 35 and mounting an alarm hand 40 radially thereon. Inwardly of the face, the shaft 38 mounts an annular cam follower 41 rigidly thereon. A cog wheel 42 is journaled on the shaft adjacent to the cam follower and provides an axially disposed notched cam 43 integral therewith engageable with the follower. The cog wheel is rotated by the timing mechanism 32. By manual rotation of the shaft by means of the head

39 the alarm hand 40 can be positioned on the face 36 at any predetermined triggering time. The cam follower 41 and cam 43 are of such co-operative form and the cam follower so positioned on the shaft 38 in relation to the hand 40 that when the triggering time is indicated by rotation of the cog wheel 42 and cam 43 the cog wheel and cam slide axially of the shaft toward the face of the clock under the urging of the spring 44 which also moves toward the face of the clock and serves to trigger an alarm structure to which attention is now directed.

A crank shaft 48 is rotatably mounted in the frame 34 and provides a winding key 49 screw-threadably mounted thereon exteriorly of the case 31. The winding key is mounted in the usual way so that its manual rotation in a direction tending to rotate the crank shaft 48 in a clockwise direction, as viewed in Fig. 5, tightens the key on the crank shaft and manual rotation of the key in the opposite direction releases the same from the shaft. In other words, the winding key limits rotation of the crank shaft 48 to a winding or clockwise direction as viewed in Fig. 5. The crank shaft has an elongated straight portion 50 intermediate the ends of which a throw 51 is radially extended to provide a journal 52 in substantially parallel relation to the straight portion.

A spiral alarm spring is mounted on the crank shaft 48 and has an end connected to the crank shaft and an opposite end fixedly mounted in the frame 34 in the well known manner. A chain of gears 55 has driven connection to the crank shaft and serves to rotate an escapement wheel 56 engageable by a releasable escapement 57. An arm 58 is extended from the escapement for latched engagement with the spring 44 whereby the escapement releasably locks the escapement wheel 56 and thus the crank shaft 48 against rotation. When the cog wheel 42 and cam 43 are permitted to move toward the face by the cam follower 41, the spring 44 moves from arm engagement and the escapement and crank shaft 48 are released for rotational movement of the crank shaft under the urging of the alarm spring 54. The timing apparatus now described including the timing mechanism 32, crank shaft 48, winding key 49, control shaft 33, head 39, alarm hand 40, cam follower 41, cog wheel 42, cam 43, spring 44, alarm spring 54, chain of gears 55, escapement wheel 56, escapement 57, and arm 58 is essentially conventional except for the utilization of the throw 51 and journal 52 and thus is not described in great particularity.

A pair of elongated arms 60 are pivotally mounted in the frame 34 as at 61 in pendent position for pivotal movement in a common plane substantially normal to the crank shaft 48.

An elongated plunger 63 is pivotally connected to the arms 60 at positions substantially equally spaced from the pivotal mountings 61 of the arms with the arms in substantially parallel relation. The arms provide a convenient mounting for the plunger in the case 31 for reciprocal rectilinear movement.

The case is provided with an opening at 65 through which an end 66 of the plunger is extended. The end 66 is provided with a longitudinal bore 67 and an elongated finger 68, conveniently taking the form of a headed bolt, is screw-threadably mounted in the bore. A jamb nut 69 is screw-threadably mounted on the finger for engagement with the end 66 of the plunger whereby the finger may be locked in adjustable telescopic relation in the plunger.

An elongated link 72 is rotatably mounted on the journal 52 of the crank shaft 48 and pivotally connected to an extended end of one of the arms 60. It will be observed in Figs. 5 and 7 that the link 72 has opposite side edges engageable with the straight portion 50 of the crank shaft 48 in parallel relation to the journal to limit rotation of the crank shaft 48 in a winding direction as shown in Fig. 7 and in an unwinding direction as shown in Fig. 5. It will be obvious that the engagement of the link with the crank shaft limits rotational movement of the crank shaft to substantially less than 360° and as coupled to the plunger rotational travel of the crank shaft between its limits serves to extend the plunger and to retract the same.

A pair of headed pins 74 are mounted in the case in substantially equally spaced relation to the end 66 of the plunger and in alignment therewith. Each of the pins conveniently consists of a sheet metal screw 75 having a washer 76 located against the head thereof, a spacing sleeve 77 mounted on the screw against the washer 76, and a washer 78 located on the screw against the sleeve 77. Tightening of the screws into the case 31 assembles the described elements of the pin tightly against the end of the case.

In certain switch panels, it is inconvenient to employ a generally U-shaped bracket as that shown at 54. In such instances brackets of the type shown at 80 in Figs. 3 and 4 are utilized. The brackets are of generally Z-shape having a pair of substantially parallel, offset, legs 81 and an interconnecting portion 82. The brackets are conveniently made of strip metal and one of the legs 81 secured to the panel 17 as by a pair of bolts 83 in a position with the opposite leg extended transversely of a push button switch 13 or 14. The leg extended across the switch has a plurality of openings 84 formed in substantially equally spaced relation in alignment therein. Each of the openings has a circular central portion and oppositely extended channels becoming in effect a double key hole opening so that the pins 74 can be rested on either end of the opening in releasable locked engagement therewith.

Operation

The operation of the described embodiment of the present invention is believed to be clearly apparent and is briefly summarized at this point. The control timer 30 is mounted with its plunger 64 and finger 68 in alignment with the switch to be operated by inserting the headed pins 74 through the openings 84 or 86 and drawing the pins downwardly into the extensions of the openings where the washers 76 releasably retain the control timer on the bracket 24 or 82. It will be apparent that the sleeve 77 is preferably substantially the length of the thickness of the brackets so that the washers 76 and 78 slidably engage opposite sides thereof. Such mounting dependably locates the control timer in precisely predetermined spaced relation to the panel 17 and switches 13 and 14 mounted thereon.

If it is desired to close the bridging element 13 to close the load circuit 22, as for starting an irrigation pump or the like, the control timer 30 is mounted with the plunger in alignment with the push button start switch 13. The head 39 is manipulated to set the alarm mechanism of the timing device for triggered operation of the crank shaft 48 at a predetermined time indicated by the hand 40 on the setting face 36 and as measured by the timing mechanism 32. The winding key 49

is turned to wind the spring 54 and to position the crank shaft 48, as shown in Fig. 7, preliminary to mounting the timer.

It will be noted that the finger 68 is telescopically mounted in the plunger 64 so that the extended end of the finger 68 is in spaced relation to the push button switch to be operated. The telescopic adjustment is secured by means of the jamb nut 69.

When the predetermined time has been measured by the timing mechanism 32 the control shaft 38 rotates to the point to which the cam 43 and cog wheel 42 moves axially of the shaft 38, to the right as viewed in Fig. 6, under the urging of the spring 44. The end of the spring 44 releases the arm 58 of the escapement 57 and the escapement wheel 56 is released so that the crank shaft 48 can turn under the urging of the spring 54. The crank shaft rotates in a counterclockwise direction, as viewed in Figs. 5 and 7, and in so doing thrusts the plunger and finger outwardly against the push button start switch 13 and retracts the plunger therefrom. Rotation of the crank shaft in the counterclockwise direction is likewise limited by engagement of the link 12 with the crank shaft.

When the start switch 13 is closed, the holding circuit of the coil 19 is completed closing the switch 18. By closing the bridging element 20, the described circuit through the coil and stop switch is also closed so that the switch 18 is in effect self-sustaining after release of the start switch. In this manner, an electrical circuit of the character described may be completed at any predetermined time without the presence of an operator.

Similarly, a completed circuit may be interrupted at any predetermined time by mounting the control timer of the present invention with the plunger 64 and fingers 68 in alignment with a stop switch 14 therein. The adjustment of the control timer and operation thereof is essentially as that already described. When the finger engages the push button stop switch 14 the switch is opened and the finger promptly withdrawn therefrom. Inasmuch as the stop switch is in series with the coil 19 and the start switch 13 is open, the circuit is broken the instant the stop switch is operated and the electrical field of the coil 19 collapses so that the sustaining switch 18 opens.

The rectilinear movement of the plunger minimizes abrasion of push buttons with which it is employed and assures proper operation by retraction from the push buttons promptly after actuation thereof. The control timer 30 is simply a mechanical alarm clock with only minor modifications for purpose of substituting the crank shaft 48 for the normal winding stem thereof and for the mounting of the cams 60 and the like. By the provision of the brackets 24 and 20 transversely of any number of switches to be operated, a single timer may be utilized in operating any selected switch of a great number thereof thus minimizing the expense necessary for controlled operation. Further, if it is desired both to start and to stop an electric pump or the like at predetermined times, a pair of control timers can be mounted on a pair of the brackets 80 illustrated in Fig. 4 and the timers set so that one thereof operates the start switch 13 at a desired time and the other the stop switch 14 in predetermined following relation thereto.

The control timer of the present invention is economical to produce, durable, easy to install

and remove, conveniently adjusted for timed operation, and a great convenience in its operation of push button switches and the like at selected times.

- 5 Although the invention has been herein shown and described in what is conceived to be the most practical and preferred embodiment, it is recognized that departures may be made therefrom within the scope of the invention, which is not to be limited to the details disclosed herein, but is to be accorded the full scope of the claims so as to embrace any and all equivalent devices, apparatus and systems.
- 15 Having described my invention what I claim as new and desire to secure by Letters Patent is:
1. In combination with an electric circuit having a push button start switch and a push button stop switch therein, means mounting the push button switches in predetermined spaced relation, a bracket mounted on the mounting means in spanning relation to the push button switches, said bracket having a plurality of key-hole openings formed therein in equally spaced relation in alignment transversely of the push button switches, a control timer having an elongated plunger mounted therein endwardly reciprocated between an extended position and a retracted position at an adjustably predetermined time measured by the control timer, and a pair of headed pins mounted on the control timer releasably engageable in the key-hole openings of the bracket in alternate positions with the plunger aligned with the push button of the start switch and the push button of the stop switch respectively.
2. In combination with an electric circuit having a push button start switch and a push button stop switch therein, means mounting the push button switches in predetermined adjacent relation, a bracket mounted on the mounting means in spanning relation to the push button switches, said bracket having a plurality of key-hole openings formed therein in equally spaced relation in alignment transversely of the push button switches, and in predetermined spaced relation thereto,
- 40 a control timer having an elongated plunger mounted therein endwardly reciprocated between an extended position and a retracted position at an adjustably predetermined time measured by the control timer, the plunger having an extended end provided with a longitudinal bore, an elongated finger screw-threadedly mounted in the bore of the plunger in alignment with the plunger for telescopic adjustment therewith, and a pair of headed pins mounted on the control timer releasably engageable in the key-hole openings of the bracket in alternate positions with the plunger aligned with the push button of the start switch and the push button of the stop switch respectively.
- 45 3. In combination with an electric circuit having a push button start switch and a push button stop switch therein, means mounting the push button switches in predetermined spaced relation, a bracket mounted on the mounting means in spanning relation to the switches, a clock having an alarm spring winding shaft therein rotated in response to predetermined travel of the clock, a case for the clock, an elongated plunger mounted in the case adjacent to the shaft for endward reciprocal movement between a position extended from the case and a relatively retracted position, means interconnecting the shaft and the plunger and reciprocating the plunger in response to shaft rotation, a stop limiting rotational travel of the shaft to an extent sufficient to achieve a single
- 55
- 60
- 65
- 70
- 75

extension and retraction of the plunger at each operation, and means borne by the case releasably engageable with the bracket in alternate positions with the plunger aligned with the push button of the stop switch and the push button of the start switch respectively and in predetermined spaced relation to the push buttons whereby the plunger is engageable therewith when extended and is disengaged therefrom when retracted.

4. In combination with an electric circuit having a push button start switch and push button stop switch therein; means mounting the push button switches in predetermined spaced relation; a bracket mounted in spanning relation to the push button switches on the mounting means; a case; a crankshaft rotatably mounted in the case having a straight portion and a throw intermediate the ends of the straight portion providing a journal in substantially parallel relation to the straight portion; an elongated plunger mounted in the case for longitudinal reciprocal movement between a position extended from the case and a retracted position in substantially transverse relation to the crankshaft; a timing device mounted in the case having driving connection to the crankshaft adapted to rotate the crankshaft in a predetermined direction at an adjustably predetermined time measured by the timing device; an elongated link having an end rotatably mounted on the journal, an opposite end pivotally coupled to the plunger, and an intermediate portion engageable with the straight portion of the crankshaft in spaced relation to the journal to limit rotation of the shaft to an extent sufficient to extend and retract the plunger; and means borne by the case releasably engageable with the bracket in alternate positions with the plunger aligned with the push button of the stop switch and the push button of the start switch respectively and in predetermined spaced relation to the push buttons whereby the plunger is engageable therewith when extended and is disengaged therefrom when retracted.

5. A control timer comprising a case, a crankshaft rotatably mounted in the case having a straight portion and a throw intermediate the ends of the straight portion providing a journal in substantially parallel relation to the straight portion, a pair of substantially parallel arms pivotally mounted in the case in pendant relation adjacent to the crankshaft for pivotal movement transversely thereof in a common plane, an elongated plunger pivotally mounted on each of the arms in substantially equally spaced relation to the pivotal mountings thereof for longitudinal reciprocal movement from and to the case, a timing device having driving connection to the crankshaft adapted to rotate the crankshaft in a predetermined direction at an adjustably predetermined time measured by the timing device, and a link pivotally interconnecting the journal of the throw of the crankshaft and an extended end of one of the arms whereby rotation of the crankshaft reciprocates the plunger between predetermined limits defined by engagement of the link with the crankshaft in spaced relation to its journal.

6. A control timer comprising a timing mechanism; means mounting the timing mechanism; a crankshaft rotatably mounted in the mounting means having a continuous elongated portion and a throw intermediate the ends of the elongated portion providing a journal in substantially parallel spaced relation to the straight portion; a

helical motivating spring mounted on the crankshaft having an end affixed thereto and an opposite end fixedly connected to the mounting means; means for rotating the crankshaft in a predetermined direction to wind the spring; an escapement releasably locking the shaft against rotation in a direction opposite to the winding direction; a linkage interconnecting the escapement and the timing mechanism for releasing the escapement in response to predetermined travel of the timing mechanism; an elongated plunger mounted in the mounting means for longitudinal reciprocal movement transversely of the crankshaft; and an elongated link having an end rotatably mounted on the journal, an opposite end pivotally coupled to the plunger, and an intermediate portion engageable with the straight portion of the crankshaft to limit rotational movement of the crankshaft in winding and unwinding directions, said link translating rotational movement of the crankshaft into longitudinal reciprocation of the plunger between limits defined by engagement of the link with the crankshaft.

7. A control timer for push button switches and the like comprising a timing mechanism, a case in housing relation to the mechanism, a crankshaft rotatably mounted in the case having a continuous elongated straight portion and a throw intermediate the ends of the straight portion having a journal in substantially parallel spaced relation to the straight portion, a helical motivating spring mounted on the crankshaft having an end anchored thereto and an opposite end fixedly mounted in the case, means for rotating the crankshaft to wind the spring, an escapement releasably locking the crankshaft against rotation, a linkage interconnecting the escapement and the timing mechanism releasing the escapement for rotation of the crankshaft in response to predetermined elapse of time as measured by the timing mechanism, a pair of substantially parallel arms pivotally mounted in the case in pendant relation adjacent to the crankshaft for pivotal movement transversely thereof in a common plane, an elongated plunger pivotally mounted on each of the arms in substantially equally spaced relation to the pivotal mountings thereof for longitudinal reciprocal movement from and to the case, and a link pivotally interconnecting the journal of the throw of the crankshaft and an extended end of one of the arms whereby rotation of the crankshaft reciprocates the plunger between predetermined limits defined by engagement of the link with the crankshaft in spaced relation to the journal.

8. A control timer for push button switches and the like comprising a case, a timing mechanism mounted in the case, a crankshaft mounted in the case having a continuous elongated straight portion and a throw intermediate the ends of the straight portion providing a journal in substantially parallel relation to the straight portion, a helical mounting spring mounted on the crankshaft having an end anchored thereto and an opposite end fixedly anchored in the case, means for rotating the crankshaft in predetermined direction to wind the spring, an escapement releasably locking the crankshaft against rotation in the direction opposite to that in which it is rotated to wind the spring, a linkage interconnecting the timing mechanism and the escapement releasing the escapement for rotation of the crankshaft by the spring in response to predetermined travel of the timing mechanism, a pair of substantially parallel arms pivotally mounted

11

in the case for pivotal movement in a common plane transversely of the crankshaft and substantially normal thereto, an elongated plunger pivotally mounted on the arms in substantially equally spaced relation to the pivotal mountings thereof interconnecting the arms in substantially parallel relation, the plunger having a longitudinal bore formed in an end thereof, an elongated finger screwthreadedly mounted in the bore of the plunger for adjustable telescopic positioning in alignment with the plunger and providing an end extended from the case, and a link rotatably mounted on the journal of the throw of the crankshaft and pivotally connected to one of the arms, said link having opposite side

10 15

12

edges adapted to engage the straight portion of the crankshaft to limit rotation of the crankshaft in winding the spring and to engage the opposite side of said straight portion of the crankshaft to limit rotation of the crankshaft in the direction motivated by the spring, the limits of the crankshaft rotation thus defined being such as to cause the plunger to extend the finger from the case and to retract the same during rotational movement of the shaft between its wound and its unwound limits.
